UNITED STATES PATENT OFFICE.

BENJAMIN HODGSON, OF PORTSMOUTH, AND STANLEY ROBERT MULLARD, OF SOUTHFIELDS, LONDON, ENGLAND.

SUPPORT FOR FILAMENTS IN THERMIONIC VALVES AND OTHER TUBES.

Application filed August 22, 1921. Serial No. 494,275.

To all whom it may concern:

Be it known that we, BENJAMIN HODGSON and STANLEY ROBERT MULLARD, residents of H. M. Signal School, Royal Naval Barracks, Portsmouth, in the county of Hants, England, and 71 Standen Road, Southfields, London, England, respectively, both subjects of the King of Great Britain, have invented certain new and useful Im-
10 provements in and Relating to Supports for Filaments in Thermionic Valves and Other Tubes (for which we have filed an application in England December 24th, 1920), of which the following is a specification.

15 This invention relates to supports for filaments in thermionic valves and other tubes, such as vacuum tubes containing fine or delicate filaments for emitting light, and more particularly for tension spring sup-
20 ports for such filaments.

According to this invention, the filament tension spring is enclosed in a tubular part of the valve or tube envelope which extends some distance from the envelope so that the 25 spring is arranged a convenient or suitable distance from the main envelope of the valve or tube. By this means the envelope of the valve or tube may be baked without a corresponding baking of the filament ten-
30 sion spring.

The invention is illustrated in the figure of the accompanying drawing. A tubular extension A of the envelope B is made sufficiently long to project outside the oven used 35 in baking the envelope during evacuation. The filament tension spring D is enclosed in the tubular part A and is arranged as far as is possible from the main envelope B. A guide piece C which may be a tube fixed 40 rigidly to the envelope B prevents lateral motion of the part at which the filament F is attached to the spring D and supporting wire E. This method of mounting the filament tension spring enables the valve or

tube to be baked without changing the initial tension applied to the filament in the assembling of the valve. The guide piece maintains the filament at a correct relative distance from the other parts of the valve or tube. The increased distance between 45 the spring and the filament avoids loss of elasticity due to heat being conveyed to the spring from the hot working parts during the normal working of the valve. The method of mounting is applicable to vacuum vessels containing any arrangement of 50 filaments and any number of electrodes.

Having thus described our invention what we claim as new and desire to secure by Letters Patent is:—

1. In combination, a vacuum tube envelope, a filament, a spring fastened to said filament, and means extending from said envelope whereby said spring maintains a uniform tension on said filament during ab-
55

normal heating of said envelope.

2. In combination, a vacuum tube envelope, a filament, a tubular portion extending from said envelope, and a spring fastened to said filament and disposed within 60 the tubular extension, whereby said spring maintains a uniform tension on said filament during abnormal heating of said envelope.

3. In combination, a vacuum tube envelope, a filament, a filament supporting wire fastened to said filament, a spring fastened to said supporting wire, a guide piece attached to the envelope for guiding the supporting wire, said guide piece separating 65 the spring from the vacuum tube envelope, and a tubular extension on the vacuum tube envelope, said extension enclosing the wire and the spring whereby said spring maintains a uniform tension on said filament 70 during abnormal heating of said envelope.

BENJAMIN HODGSON.

STANLEY ROBERT MULLARD.
